Primary Examiner — Amy C Wierenga(74) *Attorney, Agent, or Firm* — Calfee, Halter &
Griswold LLP(57) **CLAIM**We claim the ornamental design for a bridge piece, as shown
and described.**DESCRIPTION**

FIG. 1 is a front/right/top perspective view of a bridge piece;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dot broken lines and the uniformly broken lines
immediately adjacent shaded areas represent the bounds of
the claimed design. All other broken lines represent portions
of the bridge piece that form no part of the claimed design.**1 Claim, 4 Drawing Sheets****US D921,164 S**
